UNITED STATES PATENT OFFICE.

JOHN H. HALL, JR., OF PORTSMOUTH, VIRGINIA.

DESIGN FOR A WATCH-FOB.

No. 38,501.

Specification for Design.

Patented April 2, 1907.

Application filed September 1, 1906. Serial No. 333,020. Term of patent 7 years.

To all whom it may concern:

Be it known that I, JOHN HOPKINS HALL, Jr., a citizen of the United States, residing at Portsmouth, in the county of Norfolk and State of Virginia, have invented a new, original, and ornamental Design for Watch-Fobs, of which the following is a specification, reference being had to the accompanying drawing, forming part thereof.

The figure is a face view of a watch-fob, showing my new design.

I claim—

The ornamental design for a watch-fob, as shown.

J. H. HALL, JR.
